Inventor:
George Elliot Perry

By Force Bain & Hinckle
Attest.

UNITED STATES PATENT OFFICE.

GEORGE ELLIOT PERRY, OF CHICAGO, ILLINOIS, ASSIGNOR TO WILLIAM F. CUMMING, OF CHICAGO, ILLINOIS.

SIGNAL-LAMP SUPPORT.

Application filed September 8, 1921. Serial No. 499,320.

To all whom it may concern:

Be it known that I, GEORGE ELLIOT PERRY, a citizen of the United States, residing at Chicago, in the county of Cook and 5 State of Illinois, have invented certain new and useful Improvements in Signal-Lamp Supports, of which the following is a specification.

This invention relates to signal lamp supports.

One of the objects of the invention is to provide an improved signal lamp support.

Another object is to provide an improved adjustable support for mounting a signal 15 lamp on a post.

Another object is to provide a simple, reliable and inexpensive adjustable bracket for supporting a signal lamp.

Other objects and advantages will herein- 20 after appear.

An embodiment of the invention is illustrated in the accompanying drawing, wherein—

Fig. 1 is an elevation of a post and lamp support, partly in section.

Fig. 2 is an enlarged partial section of the lamp and reflector support.

Fig. 3 is a section of the reflector bracket.

Fig. 4 is a front elevation of the reflector bracket, and

Fig. 5 is a perspective of the lamp socket and its position adjuster.

The post comprises an elongated hollow casing 1, the lower end of which is adapted to be sunk into the ground or otherwise anchored in position. The upper end of the casing may be closed by a suitable cap 2 and the bottom may be closed by a suitable plug 3.

The casing may be of any desired length and cross section and may be formed from wood, pressed steel, cast iron, or other suitable material.

The inside wall of the casing is provided 45 with a number of sets of inwardly projecting lugs or shoulders 4, 5 and 6. Lugs 4 and 5 support floor panels 7 and 8, respectively. These floor panels may be made of wood or other suitable material and serve to 50 carry batteries 9 and act as partitions to divide the casing into separate compartments. There may be as many floor panels as are required for the batteries necessitated by any particular installation.

The upper set of lugs 6 serve to support

a flasher or circuit interrupter 10. Any suitable flasher may be employed. One which has given excellent results is disclosed in copending application Serial No. 395,514; filed July 12, 1920.

The casing is provided with one or more openings in its side so that access may be had to the interior for the installation, inspection and removal of the batteries and flasher. In the embodiment illustrated one opening is employed and it is closed by a door 11. The door is secured to the casing by suitable means such as hinges 12 and may be provided with latches 13 and a key actuated lock 14.

The upper end of casing 1 has a bracket 15 secured thereto. Bracket 15 is secured in place by suitable means such as screws 16, passing thru holes 17 in the bracket and threading into the post. A hole 18 passes 75 through the center of the bracket. The wall of this hole is curved or chamfered as shown.

Bracket 15 supports a reflector and lamp holder 20. The front of holder 20 is cupped 80 to fit the rear of a substantially parabolic reflector 21 and the rear end thereof is somewhat spherical to fit against the beveled wall of hole 18. Reflector 21 is secured to holder 20 in any suitable manner

The holder and reflector are adjustably held to bracket 20 by screw bolts 22. The heads of bolts 22 are set in recesses in holder 20, and the shanks thereof pass thru openings 23 in bracket 15 and aligned holes in 90 casing 1. The nuts on the adjusting screw bolts are readily accessible through the door in the casing.

The reflector holder, upon the loosening of bolts 22, may be moved in any direction 95 because of the universal joint provided by bracket 15. When the proper adjustment is secured the same may be maintained by tightening the nuts on bolts 22.

Within reflector 21, holder 20 supports a 100 lamp socket 25 for a lamp 26. The position of the lamp socket along the axis of the reflector is regulated by a screw 27. Holder 20 and the reflector have aligned holes 28 and 29 passing therethrough. 105 Holes 28 and 29 merge into each other, the latter being somewhat larger than the former. Socket 25 slidably fits in hole 28 while a lug 30 of the socket slidably fits in hole 29. Lug 30 has a threaded hole 110

therethrough for receiving screw 27. When the socket is in position the head of screw 27 abuts the rear of holder 20. Lug 30 prevents rotation of the lamp socket although the same is free to move longitudinally along the axis of the reflector. The threading of screw 27 in and out of lug 30 varies the position of lamp 26. The conducting leads 31 may pass to the lamp socket 10 through hole 29.

Having described my invention what I claim as new and desire to secure by Letters Patent, is:—

15 A signal lamp comprising a flat face support; a lamp holder to support a lamp

socket and having its rear surface substantially spherical, a bracket having a flat face and a hole therein to give access to the rear of a lamp socket and to provide a seat for the spherical end of the holder so that the 20 holder may be pivotally moved in any direction relative to the bracket, and a bolt passing thru the support, bracket and holder for holding the device on the support and the bracket and holder together in any position.

In testimony whereof I hereunto subscribed my name.

GEORGE ELLIOT PERRY.
